UNITED STATES PATENT OFFICE.

GUSTAF IVAR JOHNSON, OF MALDEN, MASSACHUSETTS.

FLASH-LIGHT.

1,366,461.

Specification of Letters Patent. Patented Jan. 25, 1921.

Application filed October 23, 1919. Serial No. 334,615.

To all whom it may concern:

Be it known that I, GUSTAF IVAR JOHNSON, a citizen of the United States of America, and a resident of Malden, in the county of Middlesex and Commonwealth of Massachusetts, have invented certain new and useful Improvements in Flash-Lights, of which the following is a specification.

This invention relates to electric flash lights and particularly to devices of this character provided with manually actuated instrumentalities for generating the current for the lamp.

The invention consists of certain novel features of construction and arrangement of parts which will be fully understood by reference to the description of the drawings and to the claims to be hereinafter given.

For the purpose of illustrating the invention one preferred form thereof is illustrated in the drawings, this form having been found to give satisfactory and reliable results, although it is to be understood that the various instrumentalities of which the invention consists can be variously arranged and organized and the invention is not limited to the precise arrangement and organization of these instrumentalities as herein shown and described, except as required by the scope of the appended claims.

30 Of the drawings:

Figure 1 represents a longitudinal section of a flashlight embodying the principles of the present invention.

Fig. 2 represents a longitudinal section 35 on line 2, 2, on Fig. 1.

Fig. 3 represents a transverse section of the same on line 3, 3, on Fig. 2.

Fig. 4 represents a transverse section on line 4, 4, on Fig. 2.

40 Figs. 5 to 10 inclusive represent similar sections on lines, 5, 5; 6, 6; 7, 7; 8, 8; 9, 9; and 10, 10 on Fig. 2, and

Fig. 11 represents a partial longitudinal section similar to Fig. 1 and showing the 45 clutch members disengaged.

Similar characters indicate like parts throughout the several figures of the drawings.

In the drawings, 10 is a frame-work having a slot 11 at one end in which is mounted the permanent magnet 12, the poles 13 of which extend toward the opposite end of said frame-work, as clearly shown in Figs. 1 and 2 of the drawings.

The opposite ends 14 and 15 of said frame-work, are cylindrical and are surrounded by a cylindrical housing 16 extending from the outer face of the end 14 to the outer face of the end 15.

One end of the housing 16 is closed by the cap 17 and surrounding the opposite end of said housing 16 is a cylindrical member 18 having a lens 19 in the outer end thereof, back of which is a reflector 20 having centrally disposed therein, an electric lamp 21.

A spring plate 22 mounted on and insulated from the frame-work 10, contacts with the lamp 21. This spring plate 22 is connected by means of a wire 23 with a contact member 24 mounted in and insulated from the frame-work 10.

The wire connection 23 is made of such diameter and length as to provide the required resistance so that only the proper amount of electric current can be conveyed to the lamp 21.

The inner end of the contact member 24 is in contact with a collar 25 mounted upon but insulated from the shaft 26 of a revoluble armature 27.

The member 24 is threaded for adjustment endwise in order to secure proper contact with the collar 25.

The opposite ends of the armature shaft 26 are cone-shaped with the points thereof positioned between a series of balls or similar anti-friction members mounted in recesses in the opposed ends of the members 28 and 29 adjustably mounted in the frame-work 10. These members 28 and 29 are in axial alignment and may be adjusted to vary the distance between the bearings for the ends of the shaft 26.

The rear end of the shaft 26 is provided with a helical thread 30 with which meshes a worm gear 31 secured to and revolubly mounted in bearings in the frame-work 10 and having secured thereto a helical pinion 33 meshing with a helical gear 34 revolubly mounted upon a stud 35 positioned in the frame-work 10.

The helical gear 34 revolves with a bevel-gear 36 meshing with another bevel-gear 37 loosely mounted upon a shaft 38, the ends of which are cone-shaped and positioned in anti-friction bearings in the opposed ends of the adjustable members 39 and 40. These members 39 and 40 are in axial alignment

and may be adjusted toward or from each other to vary the distance between the anti-friction bearings for the shaft 38.

Secured to the rear end and revoluble 5 with the shaft 38, is a clutch member 41 having secured thereto and revoluble therewith, a ratchet wheel 42 with which engages a pawl 43 pivoted at 44 to the end 15.

Loosely mounted upon the shaft 38 is a 10 worm 45 having ratchet teeth 46 cut in one end adapted to engage the teeth of the clutch member 41 when moved endwise upon said shaft 38.

In the ears 47 is mounted a pin 48 forming 15 a pintle for an operating lever 49, the shorter arm of which is provided with a segment of a gear 50, the teeth of which mesh with the teeth of the worm 45.

Normally the longer arm of the lever 49 20 rests against the periphery of the housing 16 and is held in this position by means of the slideable member 51 which is supported by a clip 52 on the housing 16.

When the flashlight is in use, the slideable 25 member 51 is in the position indicated in Fig. 1 of the drawings.

When the flashlight is not in use, the longer arm of the lever 49 is moved into contact with the periphery of the housing 16 30 and the slideable member 51 is moved so as to project over the end of said longer arm to lock said lever in inoperative position.

With the parts in the position shown in Fig. 1, the longer arm of the lever 49 is 35 moved outwardly into the position indicated in Fig. 11 by means of the spring 53 surrounding the pintle 48.

When the lever 49 is in this position, the teeth 46 are disengaged from the teeth of 40 the clutch member 41.

When hand pressure is applied to the lever 49 to move the longer arm of said lever toward the periphery of the housing 16, the segment 50 will at first move the worm 45 45 endwise until its teeth 46 have engaged the teeth of the clutch member 41 as shown in Fig. 1 of the drawings.

The continued pressure upon the longer arm of the lever 49 to move it toward said periphery, will cause the worm segment 50 50 to coat with the worm 45 and through the clutch member 41, rotate the shaft 38.

This rotary movement of the shaft 38 will be imparted to a cup-shaped casing 54 55 to which one end of a spring 55 is secured as indicated at 56 in Fig. 4 of the drawings.

The opposite end of said spring 55 has an opening therein through which extends a cam-shaped lug 57 formed upon the hub 58 60 of a disk 59 loosely mounted upon the shaft 38 and closing the end of the spring casing 54.

The bevel-gear 37 is pinned to the disk 59 and rotates therewith.

When the shaft 38 is rotated by means 65 of the lever 49, the spring 55 will be quickly wound and as soon as pressure is released from the lever 49, the unwinding of the spring 55 will cause the disk 59 and bevel-gear 37 to be rotated at a great speed. 70

This rotary movement will be transmitted through the bevel-gear 36, helical gears 34 and 33, and worm gear 31 to the helical threads 30 upon the armature shaft 26.

The armature shaft 26 will be rotated at 75 a greatly increased rate of speed over the speed of rotation of the shaft 38 owing to the ratio of the gear train interposed between said shafts.

It is obvious that the pitch of the teeth of 80 both the worm teeth 30 and the worm 45 must be such that rotary movement will be imparted thereto by the movement of the members coacting therewith.

The axis of the shaft 26 is at one side of 85 the center of the permanent magnet 12 as clearly indicated in Fig. 3 of the drawings.

The armature 27 is wound in the usual manner.

The adjustable member 28 has mounted 90 thereon, a fixed cup-shaped member 60.

Secured to and revoluble with the shaft 26 is a disk 61 extending into the open end of the cup-shaped member 60 and pivotally mounted at 62 on said disk 61, are two 95 weighted members 63 having contact projections 64 thereon.

The outer ends of these contact members 64 are adapted to bear against the inner wall of the cup-shaped member 60 and retard 100 the speed of the armature 27 when it commences to rotate too rapidly.

By means of this device, the operator by manipulating the lever 49, may rotate the armature 27 at sufficient speed to generate 105 enough electric current to light the lamp 21 and this current is maintained at a predetermined speed by means of the governor mechanism surrounding the shaft of said armature.

Means is also provided between the armature and the lamp for creating sufficient resistance to prevent any excessive amount of current being transmitted to said lamp. 110

By means of this device, the lamp may be 115 lighted at any time and is always ready for use. It dispenses with the usual batteries which are continually deteriorating and are unfit for use when most needed.

It is believed that with the foregoing explanation, the operation and many advantages of the invention will be fully understood without further description.

Having thus described my invention, I claim:

1. In a device of the class described, the combination of a framework; a lamp at one end thereof; a permanent magnet mounted

in said framework with its poles extending away from said lamp; a rotatable armature positioned between and lengthwise of the poles of said magnet; electric connections between said lamp and armature; and a manually actuated device for imparting rotary movement to said armature.

2. In a device of the class described, the combination of a framework; a permanent magnet mounted in one end thereof; a rotatable armature positioned between the poles of said magnet and at one side of the longitudinal center of the poles thereof; a lamp; electric connections between said lamp and armature; and a manually actuated device for imparting rotary movement to said armature.

3. In a device of the class described, the combination of a framework; a lamp at one end thereof; a permanent magnet mounted in said framework with its poles extending away from said lamp; a rotatable armature positioned between and lengthwise of the poles of said magnet; a shaft on which said armature is mounted; anti-friction bearings on said framework in which the ends of said shaft are positioned; electric connections between said lamp and armature; and a manually actuated device for imparting rotary movement to said armature.

4. In a device of the class described, the combination of a framework; a lamp at one end thereof; a permanent magnet mounted in said framework with its poles extending away from said lamp; a rotatable armature positioned between and lengthwise of the poles of said magnet; a shaft on which said armature is mounted having cone-shaped ends; anti-friction bearings on said framework in which the ends of said shaft are positioned; electric connections between said lamp and armature; and a manually actuated device for imparting rotary movement to said armature.

5. In a device of the class described, the combination of a framework; a lamp at one end thereof; a permanent magnet mounted in said framework with its poles extending away from said lamp; a rotatable armature positioned between and lengthwise of the poles of said magnet; electric connections between said lamp and armature; a shaft for said armature having a worm formed thereon; a worm wheel meshing with said worm; and means for imparting rotary movement to said worm wheel.

6. In a device of the class described, the combination of a framework; a permanent magnet mounted in one end thereof; a rotatable armature positioned between and lengthwise of the poles of said magnet; a lamp; electric connections between said lamp and armature; a shaft for said armature having a worm formed thereon; a worm wheel meshing with said worm; and spring

actuated means for imparting rotary movement to said worm wheel.

7. In a device of the class described, the combination of a framework; a permanent magnet mounted in one end thereof; a rotatable armature positioned between and lengthwise of the poles of said magnet; a lamp; electric connections between said lamp and armature; a shaft for said armature having a worm formed thereon; a worm wheel meshing with said worm; a spring for imparting rotary movement to said worm gear; and manually actuated mechanism for winding said spring.

8. In a device of the class described, the combination of a framework; a permanent magnet mounted in one end thereof; a rotatable armature positioned between the poles of said magnet; a lamp; electric connections between said lamp and armature; a shaft for said armature having a worm formed thereon; a worm wheel meshing with said worm; a train of gears for imparting rotary movement to said worm gear; a spring for actuating the initial gear of said train and connected at one end thereto; a spring casing to which the opposite end of said spring is connected; a shaft to which said casing is secured and on which said initial gear is free to rotate; and a manually actuated mechanism for rotating said shaft.

9. In a device of the class described, the combination of a framework; a permanent magnet mounted in one end thereof; a rotatable armature positioned between the poles of said magnet; a lamp; electric connections between said lamp and armature; a shaft for said armature having a worm formed thereon; a worm wheel meshing with said worm; a train of gears for imparting rotary movement to said worm gear; a spring for actuating the initial gear of said train and connected at one end thereto; a spring casing to which the opposite end of said spring is connected; a shaft to which said casing is secured and on which said initial gear is free to rotate; a clutch member secured to said casing shaft; a second clutch member loosely mounted upon said shaft and movable endwise; and means for engaging said clutch members and imparting rotary movement thereto.

10. In a device of the class described, the combination of a framework; a permanent magnet mounted in one end thereof; a rotatable armature positioned between the poles of said magnet; a lamp; electric connections between said lamp and armature; a shaft for said armature having a worm formed thereon; a worm wheel meshing with said worm; a train of gears for imparting rotary movement to said worm gear; a spring for actuating the initial gear of said train and connected at one end

- thereto; a spring casing to which the opposite end of said spring is connected; a shaft to which said casing is secured and on which said initial gear is free to rotate; a clutch 5 member secured to said casing shaft; a second clutch member loosely mounted upon said shaft and movable endwise; means for engaging said clutch members and imparting rotary movement thereto; and 10 means for preventing said casing shaft rotating in a reverse direction.
11. In a device of the class described, the combination of a framework; a permanent magnet mounted in one end thereof; a rotatable armature positioned between the poles of said magnet; a lamp; electric connections between said lamp and armature; a shaft for said armature having a worm formed thereon; a worm wheel meshing 15 with said worm; a train of gears for imparting rotary movement to said worm gear; a spring for actuating the initial gear of said train and connected at one end thereto; a spring casing to which the opposite end of said spring is connected; a shaft to which said casing is secured and on which said initial gear is free to rotate; a clutch member secured to said casing shaft; a second clutch member loosely mounted upon 20 said shaft and movable endwise; said clutch member having a helical thread on its periphery; a gear segment meshing with said helical thread; and manually actuated mechanism for imparting movement to said segment.
12. In a device of the class described, the combination of a framework; a permanent magnet mounted in one end thereof; a rotatable armature positioned between the poles 25 of said magnet; a lamp; electric connections between said lamp and armature; a shaft for said armature having a worm formed thereon; a worm wheel meshing with said worm; a train of gears for imparting rotary movement to said worm gear; a spring for actuating the initial gear of said train and connected at one end thereto; a spring casing to which the opposite end of said spring is connected; a shaft to which said casing 30 is secured and on which said initial gear is free to rotate; a clutch member secured to said casing shaft; a second clutch member loosely mounted upon said shaft and movable endwise, said clutch member having a helical thread on its periphery; a pivoted gear segment meshing with said helical thread; and manually actuated mechanism for imparting movement to said segment.
13. In a device of the class described, the combination of a framework; a permanent magnet mounted in one end thereof; a rotatable armature positioned between and lengthwise of the poles of said magnet; a lamp; electric connections between said lamp and armature; a rotatable shaft for said 35
- armature; and a governor for controlling the speed of said armature.
14. In a device of the class described, the combination of a framework; a permanent magnet mounted in one end thereof; a rotatable armature positioned between and lengthwise of the poles of said magnet; a lamp; electric connections between said lamp and armature; a fixed cup-shaped member on said framework; a shaft for said 40 armature; a member rotatable with said armature shaft; and friction members carried by said rotatable member and coating with said cup-shaped member to control the speed of said armature.
15. In a device of the class described, the combination of a framework; a permanent magnet mounted in one end thereof; a rotatable armature positioned between and lengthwise of the poles of said magnet; a lamp; electric connections between said lamp and armature; a rotatable shaft for said armature; and aligned members adjustably mounted in said framework provided with opposed bearings for said armature 45 shaft.
16. In a device of the class described, the combination of a framework; a permanent magnet mounted in one end thereof; a rotatable armature positioned between and lengthwise of the poles of said magnet; a rotatable shaft for said armature; a lamp; electric connections between said lamp and armature; members threaded to said framework in axial alinement; and anti-friction 50 members in the opposed ends of said aligned members adapted to support the opposite ends of the armature shaft.
17. In a device of the class described, the combination of a framework; a permanent magnet mounted in one end thereof; a rotatable armature positioned between and lengthwise of the poles of said magnet; a lamp; a rotatable shaft for said armature; a collar on said armature shaft; a member contacting therewith; a member contacting with said lamp; and wire connections between said contact members.
18. In a device of the class described, the combination of a framework provided with a transverse slot at one end; a permanent magnet supported in said slot with its pole members extending lengthwise of said framework; a casing fitted over said framework; a lamp mounted thereon; and an armature revolvably mounted on said framework electrically connected to said lamp, said armature being rotatable about an axis parallel with the poles of said magnet.
19. In a device of the class described, the combination of a framework; a magneto-generator on said framework including an armature rotatable about an axis lengthwise of said framework; a lamp; electric connections between said lamp and generator;

spring actuated mechanism for imparting rotary movement to said armature; and a lever pivoted to said frame-work and adapted to place said spring mechanism in operation.

20. In a device of the class described, the combination of a frame-work; a magneto-generator on said frame-work including a rotating armature; a lamp; electric connections between said lamp and generator; a spring actuated mechanism for imparting rotary movement to said armature; a lever pivoted to said frame-work and adapted to place said spring mechanism in operation; a 10 casing surrounding said frame-work; and a 15 slideable member thereon adapted to lock said lever against said casing when the lamp is not in use.

21. In a device of the class described; the combination of a magneto-generator including a rotating armature; a shaft for said armature extending lengthwise of said device; a lamp; electric connections between said lamp and generator; and means 25 surrounding the armature shaft for controlling the speed of said rotating armature.

22. In a device of the class described, the combination of a magneto-generator including a rotating armature; a shaft for said 30 armature extending lengthwise of said device; a lamp; electric connections between said lamp and generator; and automatic means surrounding the armature shaft for

controlling the speed of said rotating armature. 35

23. In a device of the class described, the combination of a magneto-generator including a rotating armature extending lengthwise of said device; a revoluble shaft on which said armature is mounted; a lamp; 40 electric connections between said lamp and generator; and a governor on said shaft and rotatable therewith.

24. In a device of the class described, the combination of a magneto-generator including a rotating armature extending lengthwise of said device; a revoluble shaft on which said armature is mounted; a lamp; 45 and an electric connection between said lamp and generator having a resistance therein. 50

25. In a device of the class described, the combination of a magneto-generator including a rotating armature extending lengthwise of said device; a revoluble shaft on which said armature is mounted; a lamp; 55 and wire connections between the lamp and generator of sufficient size and length as to create the required resistance to the electric current.

Signed by me at 746-7 Old South Bldg., 60 Boston, Mass., this 10th day of October, 1919.

GUSTAF IVAR JOHNSON.
